(57) **CLAIM**

The ornamental design for a remote-controlled toy ship, as shown and described.

DESCRIPTION

FIG. 1 is a perspective view of a combined remote-controlled toy ship and controller showing my new design;

FIG. 2 is a front elevational view of the ship part;

FIG. 3 is a rear elevational view thereof;

FIG. 4 is a right side view thereof;

FIG. 5 is a left side view thereof;

FIG. 6 is a bottom plan view thereof;

FIG. 7 is a top plan view thereof;

FIG. 8 is a front elevational view of the controller part;

FIG. 9 is a rear elevational view thereof;

FIG. 10 is a right side view thereof;

FIG. 11 is a left side view thereof;

FIG. 12 is a bottom plan view thereof; and,

FIG. 13 is a top plan view thereof.

The broken lines shown depict portions of the remote controlled toy ship that form no part of the claimed design.
